UNITED STATES PATENT OFFICE.

JOHN EDEN, OF ATTLEBOROUGH, MASSACHUSETTS.

DESIGN FOR A STANDARD FOR CLOTHES-DRIERS.

SPECIFICATION forming part of Design No. 26,496, dated January 5, 1897.

Application filed October 15, 1896. Serial No. 609,027. Term of patent 7 years.

To all whom it may concern:

Be it known that I, JOHN EDEN, a citizen of the United States, residing at Attleborough, in the county of Bristol and State of Massachusetts, have invented and produced a new and original Design for a Standard for Clothes-Driers; and I do hereby declare the following to be a full, clear, and exact description of the same, reference being had to the accompanying drawing, forming a part thereof.

The drawing shows a front elevation of my design.

The leading features of my design are a vertical rectangular plate A, with a projecting horizontal semicircular flange or base D at the bottom and an oval semicircular cap B at the top, with radial slots e e made in it. A straight rectangular bar C extends up from the cap B of the rectangular plate and is sur-

mounted by an oval semicircular cap E, having radial slots a a made in it. 20

What I claim as my invention is—

The design for a standard for a clothes-drier herein shown and described, consisting of a vertical rectangular plate having a projecting horizontal flange or base and an oval cap with radial slots made in it, a straight rectangular bar extending up from the cap of the rectangular plate and surmounted by an oval semicircular cap having radial slots 30 made therein. 25

In testimony whereof I affix my signature in presence of two witnesses.

JOHN EDEN.
